THREE WAY COCK.

APPLICATION FILED AUG. 29, 1904. RENEWED JAN. 4, 1907.

2 SHEETS-SHEET 2.

UNITED STATES PATENT OFFICE.

EDWIN A. HALL, OF HYDE PARK, MASSACHUSETTS, ASSIGNOR TO AIRIFIED GAS HEATING AND POWER COMPANY, OF BOSTON, MASSACHUSETTS, A CORPORATION OF ARIZONA TERRITORY.

THREE-WAY COCK.

No. 862,783.

Specification of Letters Patent.

Patented Aug. 6, 1907.

Application filed August 29, 1904, Serial No. 222,628. Renewed January 4, 1907. Serial No. 350,821.

To all whom it may concern:

Be it known that I, EDWIN A. HALL, of Hyde Park, in the county of Norfolk and State of Massachusetts, have invented certain new and useful Improvements 5 in Three-Way Cocks, of which the following is a specification.

This invention relates to cocks adapted to direct an impelling fluid under pressure alternately in different directions to instrumentalities such as two alternately- 10 acting hydraulic motors, and expelling the exhaust of the impelling fluid from each instrumentality or motor when the impelling fluid is admitted to the other.

The invention is here shown as embodied in an apparatus 15 for forcing air or air and gas continuously to a mixing-chamber by an alternate action of two pumps, each of which comprises an inverted air-receiving bell which is raised by the introduction of water under pressure into a hydraulic motor, and is released by 20 the connection of the motor with an exhaust passage.

The invention consists in the improvements which I will now proceed to describe and claim.

Of the accompanying drawings, forming a part of this specification,—Figure 1 represents a partial sectional 25 view and partial side elevation of a three-way cock embodying my invention. Fig. 2 represents a section on line 2—2 of Fig. 1. Fig. 3 represents a section on line 3—3 of Fig. 1. Fig. 4 represents a side elevation showing my improved three-way cock applied to an 30 air-forcing or pumping apparatus.

The same reference characters indicate the same parts in all the figures.

In the drawings,—*a a'* represent two tanks, each open at its upper end, and adapted to hold a body of 35 water.

b b' represent inverted air-pumping tanks or air-bells, each open at its lower end, the said bells being movable vertically in the tanks *a a'*, and sealed at their lower ends by the water in the tanks, each tank and 40 bell constituting an air-pump. Into each bell extends an air-induction pipe *c* open to the atmosphere at the bottom of the tank, and extending above the sealing liquid, the said pipe having valves at its upper portion, adapted to permit the entrance of air to the 45 bell, and prevent the escape of air from the bell, through the pipe *c*. From each bell extends an air-outlet pipe *d*, which passes through the bottom of the tank and communicates with the bell above the sealing liquid. Each bell is alternately raised to draw air 50 through its induction-pipe, and released and allowed to descend from its raised position to force the air through the outlet-pipe, this being effected by hydraulic motors in the tanks *a a'*. Each motor comprises a cylinder *e* affixed to the bottom of the tank, a

piston *e'* in the cylinder, and a rod *e''* extending through 55 a stuffing-box at the upper end of the cylinder and secured to the head of the bell. Water under pressure is alternately admitted to and shut off from the cylinder, the water raising the piston and the bell connected therewith. When the water is shut off from the cylinder, a vent from the latter is opened, so that the water in the cylinder is released, and the piston and bell are allowed to descend, the descent of the bell forcing the air through the outlet-pipe. The two motors are operated alternately, so that when one air-bell is rising, 60 the other is descending. To this end, water is admitted to the cylinders *e e'*, alternately, by the means next described.

g represents a valve-casing having an inlet-branch *g'* connected by a pipe *g''* with a source of supply of 70 water under pressure, and supported by a standard *g''* in suitable proximity to the tanks *a a'*. The valve-casing *g* is provided with two oppositely extending outlet-branches *g'' g'''*, one of which is connected by a pipe *g''* with the cylinder in the tank *a*, and the other 75 by a pipe *g''* with the cylinder in the tank *a'*. The branch *g''* is connected by a waste-passage *g''* with one side of the valve-casing, while the branch *g'''* is connected by a waste-passage *g''* with the opposite side of the casing, the waste-passages communicating with 80 the casing at different distances from the branches *g'' g'''*, which are in alignment with each other.

g'' g'''' represent waste-outlets in the casing *g*, the outlet *g''* being operatively related to the waste-passage *g''*, while the outlet *g''''* is operatively related to the 85 waste-passage *g''*.

h represents a cylindrical valve fitted to rotate in the casing *g* and provided with a passage *h'* (Fig. 3) adapted to connect the inlet-passage *g'* with either the outlet-branch *g''* or the outlet-branch *g'''*, a quarter- 90 rotation of the valve being sufficient to change the connection. The valve has a pair of waste-ports *h'' h'''*, adapted to register respectively with the waste-passage *g''* and the waste-passage *g''*. The valve also has another pair of waste-ports *h'''' h'''''*, adapted to register respectively 95 with the waste-passage *g''* and the waste-outlet *g''''*. The valve is chambered, to connect the ports of each pair, as shown in Fig. 2. The valve is partially rotated during the upward movements of each air-bell, by mechanism hereinafter described, the organization 100 being such that when one bell approaches the extreme of its upward movement, the valve is turned to shut off the impelling water from the motor of that bell, and at the same time connects said motor with one of the waste-outlets, the valve also at the same time admitting water to the motor of the other air-bell, and disconnecting the last-mentioned motor from the corresponding waste-outlet, so that each bell commences to 105

rise when the other commences to descend. When the valve is in the position shown in Figs. 1 and 3, the inlet-branch g' is connected by the valve-passage h' with the outlet-branch g^4 communicating with the cylinder of the motor in the tank a' , and the cylinder of the motor in the tank a is connected through the waste-passage g^7 of the casing and the ports $h^2 h^3$ of the valve, with the waste-pipe g^9 . When the valve is in its opposite position, the inlet-branch g' is connected by the valve-passage h' with the outlet-branch g^4 communicating with the motor cylinder in the tank a , the motor cylinder in the tank a' being connected through the waste-passage g^8 of the casing and the ports $h^4 h^5$ of the valve, with the waste-pipe g^{10} .

15 The mechanism for turning or shifting the valve is described as follows: $i i^2$ are three arms radiating from a hub i^3 , which is adapted to turn on a short shaft j , to which is affixed a bevel-gear j' . The arms $i i^2$ project in opposite directions, and are at right angles with the 20 arm i' . Each of the arms $i i^2$ has a stud i^4 at its outer end, adapted to engage a dog i^5 , which moves with the adjacent air-bell. Each bell carries a dog i^6 , which is connected with the bell by a rod i^6 affixed to an arm i^7 on the upper portion of the bell and movable in 25 guides i^8 on the corresponding tank. The bevel-gear j' on said shaft meshes with a bevel-gear j^3 affixed to the stem of the valve h . The central arm i' has an extension i^9 pivoted to it at i^{10} , said extension having a weight i^{12} . The arm i' also has two oppositely extending 30 projections $i^{13} i^{14}$, adapted to abut against fixed stops $i^{15} i^{16}$ at opposite sides of the center of oscillation of the arm.

I will assume that the bell b' in rising has caused its dog i^5 to engage the stud i^4 on the arm i^2 . The 35 movement imparted to the dog while it is engaged with said stud is sufficient to move the arms $i i^2$ and extension i^9 from the position shown in Fig. 1, toward the position shown in Fig. 4, the arm i' being moved in the direction of the arrow in Fig. 1, until the weight- 40 ed extension has crossed the center of motion, whereupon, the said extension and the connected parts move by gravitation to the position shown in Fig. 4. The gear j' has a stud j^5 , which projects between the arms i' and i^2 . When the said arms are in the position shown 45 in Fig. 1, the arm i' bears against said stud, the latter being separated from the arm i^2 ; consequently during a part of the above-described movement of the connected arms, the stud j^5 and gear j' remain stationary, the arrangement being such that the arm i^2 strikes the 50 stud during the latter or gravitating portion of its movement, and gives the gear a suitable partial rotation to shift the valve from one position to the other. The arm i' , its extension i^9 , and the arms $i i^2$ constitute a gravity motor which is set for action by the rise of the 55 bells $b b'$, and then operates by gravitation independently of said bells. The provision afforded by the

stud j^5 and arms $i i^2$ for a considerable movement of said motor before it engages and moves the gear j' enables the motor to have a movement of sufficient amplitude, and to move the valve quickly during the 60 latter part only of its movement. The pivotal connection between the arm i' and the weighted extension i^9 enables the extension to move to a limited extent, independently of the arm, the extension swinging on the pivot i^{10} to the extent permitted by shoulders i^{20} 65 on the extension and the projections $i^{13} i^{14}$ on the arm. This independent movability of the extension increases its momentum during the gravitating movement of the motor.

The construction shown in Fig. 4 is a part of an apparatus for mixing air and gas set forth and claimed in another application for Letters Patent of the United States filed by me August 25, 1904, Serial No. 222,103. I do not however, limit myself to the use of the improved three-way cock above described in said apparatus, as the said cock may be used for any other purpose to which it may be found applicable.

I claim:-

1. A three-way cock comprising a casing having an inlet-branch communicating with a source of fluid-supply, 80 two outlet-branches communicating with said casing at points coinciding with the inlet-branch, and two waste-passages connecting the outlet-branches with the casing at different distances from the inlet-branch, a rotary valve in said casing having two chambers at different distances 85 from the inlet-branch, each chamber having two waste-ports, and means for rocking or partially rotating the valve.

2. A three-way cock comprising a casing having an inlet-branch communicating with a source of fluid-supply, 90 two outlet-branches communicating with said casing at points coinciding with the inlet-branch, and two waste-passages connecting the outlet-branches with the casing at different distances from the inlet-branch, a rotary valve in said casing having two chambers at different distances 95 from the inlet-branch, each chamber having two waste-ports, a gear affixed to the stem of said valve, an operating gear meshing therewith, an oscillatory lever adapted to partially rotate said operating gear in opposite directions, and means for oscillating said lever.

3. A three-way cock comprising a casing having an inlet branch communicating with a source of fluid supply, two outlet branches extending from said casing, and two waste passages connecting the outlet branches with two waste outlets in the casing, a rotary valve in said casing 105 adapted to connect the inlet branch of the casing with the two outlet branches alternately and to connect the waste passages of the casing alternately with the waste-outlets, an operating member j' geared to said valve and having a stud or projection j^5 , a pivoted weighted lever 110 having means for engaging said stud, and means for moving said lever into position to operate by gravity.

In testimony whereof I have affixed my signature, in presence of two witnesses.

EDWIN A. HALL.
